BOOKBINDER

Arthur E. Bloomfield and William E. Smith,
West Webster, N. Y.

Application June 17, 1936, Serial No. 85,786

13 Claims. (Cl. 129—40)

The invention relates to a bookbinder for binding books, magazines, catalogues, pamphlets, booklets, leaflets and the like whether composed of few or many leaves and whether bound or unbound or provided with stiff or flexible covers. The term "books" as used for the following description and claims is used in its broad sense to include all of the above or similar book-like articles.

10 The object of the present invention is to provide for use in libraries, reading rooms, homes and other places a simple, practical and efficient bookbinder of strong, durable and comparatively inexpensive construction adapted to bind securely a single book or a plurality of books of the same size or of different sizes and capable of enabling a book or books to be easily and quickly placed in and removed from the bookbinder.

15 Another object of the invention is to provide a bookbinder of this character having a cover element composed of a back and stiff hinged leaves and provided at the inner face of the back between the leaves with a bookholder and having at the top and bottom thereof book engaging means for retaining a book or a plurality of books in the holder.

20 A further object of the invention is to provide a bookbinder having a bookholder of channel formation presenting parallel side walls to a book or books and adapted when filled to embrace closely or tightly a book or books and cooperate with the bookholding means to prevent effectually the book or books from pulling 35 out of the holder.

25 Another object of the invention is to provide a bookbinder equipped with laterally adjustable book engaging means and provided with closure members for the holder adapted to be securely locked in position so that when desired they may be removed only by the use of a key or similar instrument.

30 Another object of the invention is to provide a bookbinder having such closure members provided with locking means adapted to be operated without the use of a key or similar instrument.

35 A further object of the invention is to provide book engaging means consisting of separate clips having front and rear legs adapted to straddle the holder and provided with terminal eyes or loops adapted to facilitate the placing of the spring clips in their engaging position and capable of enabling them to be engaged with books 50 of different sizes without liability of injuring the

paper or other material of which a book may be made.

It is also an object of the invention to provide a bookbinder which will permit the leaves of a book or books when opened to lie flat in such open position.

With these and other objects in view, the invention consists in the construction and novel combination and arrangement of parts herein-after fully described, illustrated in the accompanying drawings and pointed out in the claims hereto appended, it being understood that various changes in the form, proportion and details of construction, within the scope of the claims, may be resorted to without departing 15 from the spirit or sacrificing any of the advantages of the invention.

In the drawings:

Fig. 1 is a perspective view of a bookbinder constructed in accordance with this invention, 20 one of the hinged leaves of the cover element being broken away and shown in section.

Fig. 2 is a longitudinal sectional view of the same taken on the line 2—2 of Fig. 3, the holder being in an upright position.

Fig. 3 is a horizontal sectional view on the line 3—3 of Fig. 2, the cover element being opened out flat and broken away.

Fig. 4 is a transverse sectional view taken substantially on the line 4—4 of Fig. 2, the cover element being opened out flat and a booklet of two leaves being shown in the holder for convenience of illustration.

Fig. 5 is a detail perspective view of the key for holding the lugs of the closure member out of engagement with the side walls or flanges of the holder to permit removal of the closure member.

Fig. 6 is a detail horizontal sectional view similar to a portion of Fig. 3 and showing the key in operative position, the closure member being shown in full lines disengaged from the holder and in dotted lines removed therefrom.

Fig. 7 is a horizontal sectional view of a bookbinder illustrating a modification of the invention and showing in the binder a plurality of books or booklets shorter than the holder.

Fig. 8 is a similar view, the section being taken on the lower plane than that of Fig. 7 to show in plan view the lugs of the closure members squared at each end.

Fig. 9 is a longitudinal sectional view illustrating another modification of the invention, the holder being provided at its rear face only with a channel.

Fig. 10 is a plan view partly in section showing one end of the binder of Fig. 9 and illustrating in plan view the lugs of the closure member beveled at both ends.

5 Fig. 11 is a transverse sectional view taken on the line 11—11 of Fig. 10.

Fig. 12 is a detail transverse sectional view illustrating another modification of the invention in which the holder is corrugated.

10 Referring particularly to the form of the invention illustrated in Figs. 1 to 6, inclusive, of the drawings, the bookbinder is provided with a cover element 1 composed of a back 2 and hinged leaves 3 preferably made of board or other suitable stiff 15 material and preferably covered at the inner and outer faces with cloth, "leatherette" or other suitable material. The back is preferably composed of a stiff strip 4 of board or other suitable material and is faced with a piece 5 of fabric or 20 other suitable material interposed between the strip 4 and a holder 6 and extended beyond the same and secured by adhesive or other suitable material to the inner faces of the hinged leaves. The outer covering 7 of the hinged leaves 3 is 25 preferably extended across the strip 4 in the formation of the back of the cover element and is secured by adhesive material or other suitable means to the strip 4. The cover element 1 may however be made in any other desired manner 30 and may be variously ornamented as will be readily understood.

The holder 6 is preferably of double channel formation to provide a front channel 8 and a rear channel 9. The holder is designed to be 35 stamped or otherwise formed from a single substantially oblong piece of sheet metal which is bent at right angles at spaced points to provide parallel front flanges 10 and a connecting web 11. The metal of the flanges 10 is then folded 40 back upon the flanges at each side of the holder and extended rearwardly beyond the web 11 to provide spaced parallel rearwardly extending flanges 12 which form the side walls of the rear channel 9. The rear flanges 12 are fitted against 45 the back of the cover element and may be secured to the stiff strip 4 by tubular rivets 13, as clearly illustrated in Fig. 2 of the drawings, but any other suitable fastening means may of course be employed. The rivets 13 pierce the strip 4 50 and terminate short of the outer face of the cover element. The fabric member 5 assists in securing the holder to the cover element as the fabric element extends across the strip 4 between the same and the holder and is secured to the hinged leaves of the cover element.

The front channel of the holder is adapted to receive one or more books which are retained in the front channel by spring clips 14 located at the upper and lower ends of the holder and 60 constructed of spring steel wire or other suitable material and composed of front and rear legs 15 and 16 and a curved connecting portion 17. The resilient book engaging clips 14 which may be of any desired number and which are laterally adjustable on the end portions of the holder have their front legs located in the front channel 8 and their rear legs arranged in the rear channel 9. The front leg 15 of each book engaging clip is straight and is designed to be of greater length 65 than the rear leg 16 for engaging books of different sizes and regardless of the thickness of a book it is adapted to lie flat against the binding of the book in parallelism with the web 11 of the holder and it is provided at its free end with 70 a relatively large circular loop 18 forming an eye

adapted to be readily grasped between the fingers to facilitate the removal of the spring clips from the holder. Also the eye formed by the loop 18 is adapted to be readily engaged by a key 19 or other instrument to facilitate removal of the 5 spring clips and the terminal loop 18 enables the spring clips to be readily engaged with a book without liability of injuring the leaves or binding thereof. The rear leg is provided with an angular bend 20 which fits against the rear face of the 10 web 11 of the holder when the clip is in position on the holder and it forms a fulcrum and it coacts with the curved connecting portion of the clip to enable the front leg to be arranged in 15 parallelism with the web portion of the holder when the said front leg is in engagement with the binding of a book regardless of the thickness of the book. The major portion of the rear leg 16 is straight and is arranged at an acute angle 20 to the straight front leg 15, and its free terminal bears against and fulcrums on the rear face of the holder. The curved connecting portion 17 of the clip is resilient and forms with the front and rear legs a tapering spring loop which is adapted 25 to adjust itself automatically to the thickness of a book with the straight front leg lying flat against the book. The resilient connecting portion of the loop and the fulcruming of the free end of the rear leg against the holder permit the front leg to maintain itself in parallelism with the 30 holder and lie flat against a book at different distances from the holder so that it will always lie flat against a book regardless of the thickness of the same. The rear leg is provided at its free 35 end with a substantially circular loop 21 of a size to lie within the rear channel of the holder. The spring clips may be arranged at either or both ends of the holder for temporary or permanent binding and, when arranged at one end only at either the top or bottom of the holder, books, 40 catalogues, pamphlets, leaflets and the like of different sizes may be readily placed in and removed from the binder by simply engaging them with and disengaging them from the front legs of the clips without removing the clips from the 45 holder.

The spring clips are moved lengthwise of the holder to engage them with and disengage them from the holder and they are retained in position on the holder by closure members 22 constructed of sheet metal or other suitable material and consisting of a substantially L-shaped plate provided with side flanges 23 and having spaced longitudinally extending resilient ears 24 formed integral with and extending from the 55 flanges 23 and arranged within the rear channel 9 and fitted flat against the inner faces of the side walls or flanges 12 of the rear channel. The L-shaped plate of the closure member is composed of wings 25 and 26; the wing 25 fits between the rearwardly extending flanges 12 of the holder and the other wing 26 extends across the end of the holder and with the side flanges 23 confines the spring clips 14 on the holder. The side flanges of the closure member extend from 60 the wing 26 and abut against the front flanges 10 of the holder.

The resilient arms 24 of the closure member are provided at their inner ends with laterally extending lugs 27 which project into slots 28 in 70 the side walls or flanges 12 of the rear channel 9 of the holder, as clearly illustrated in Fig. 3 of the drawings. The lugs 27 are shouldered at one end at 29 and are beveled at 30 to facilitate the ready insertion of the arms 24 into the rear chan- 75

nel and to provide a locking engagement between the lugs 27 and the outer end walls of the slots 28 when the closure members are in their locked position.

5 The shoulders 29 prevent the closure members from being withdrawn from the rear channel of the holder until the lugs 27 are disengaged from the slots 28. When the lugs 27 are pressed inwardly out of engagement with the slots 28 the closure member may be readily withdrawn from the rear channel of the holder.

In order to facilitate the ready removal of the closure member the substantially U-shaped key 19 is provided. The key 19 which is preferably constructed of spring metal is composed of spaced sides and a connecting portion. The free terminals 31 of the sides of the key are bent inwardly at right angles and are reduced in width to form projecting fingers 32 which are of a size to extend 20 through the slots 28 and force the lugs 27 inwardly out of engagement with the slots, as clearly illustrated in Fig. 6 of the drawings. When the lugs 27 are moved inwardly out of engagement with the slots 28 as illustrated in Fig. 6 the closure member may be readily withdrawn from the holder and removed therefrom as indicated in dotted lines in Fig. 6 of the drawings. This exposes the spring clips and enables the latter to be readily removed and replaced as required.

30 In Fig. 1 of the drawings a single book 33 which may consist of a magazine or catalogue or the like is arranged in the holder and completely fills the same and is of a length substantially equal to the length of the holder. In Fig. 7 a plurality of books 34 are shown arranged within the holder 35 and of a length less than the length of the holder. The holder 35 which is of substantially the same construction as that heretofore described is shown provided with a plurality of 40 spring clips at each end. The spring clips may be of any desired number and are retained in place by closure members 36 constructed the same as those heretofore described with the exception that the arms 37 are provided with lugs 38 which are squared at both ends and which require a key to enable the closure members to be removed from the holder. The holder 35 has front and rear channels, as clearly shown in Figs. 7 and 8 of the drawings, and the arms 37 are located within the rear channel. The holder 35 is designed to be secured to a cover element 39 similar to that heretofore described and in the same manner as heretofore explained in connection with the holder 6.

55 In Figs. 9 to 11, inclusive, of the drawings is illustrated a holder 40 of channel formation consisting of rearwardly extending flanges 41 and a connecting web 42, the front channel of the holders heretofore described being omitted. The holder 40 is relatively wide and is particularly adapted for holding a large number of books of the smaller type such as pamphlets. The pamphlets or booklets are secured on the holder by spring clips 14 which are retained in positioned on the holder by closure members 43 constructed substantially the same as the closure members heretofore described with the exception that the resilient arms 44 are provided with lugs 45 beveled at each end to enable them to be readily disengaged from the slots 46 without the use of a key or other instrument. The beveled lugs 45 will enable the closure members 43 to be readily applied to and removed from the holder 40.

In Figure 12 of the drawings is illustrated another modification of the invention in which the

holder 47 is corrugated, forming a plurality of channels and apices at the front and back of the holder to space the spring clips and yet allow lateral movement or adjustment of the spring clips on the holder. The channels and apices at 5 the front of the holder permit books to be arranged in staggered relation with the thicker back portions arranged alternately in the channels 48 and on the apices 49 at the front of the holder. By staggering the backs of the books in 10 this manner, more books may be placed in the bookbinder than is possible where the holder has a continuous flat surface to receive the books. The front legs of the spring clips lie flat against the books while the rear legs of the spring clips 15 are located at the channels 49^a and apices 50 formed by the corrugations at the back of the holder.

What is claimed is:

1. A binder for books, magazines, pamphlets 20 and the like, comprising a holder having side walls and a connecting web, the side walls projecting forwardly and rearwardly beyond the connecting web and forming front and rear longitudinal channels, the front channel being arranged to receive the books, magazines, catalogues, pamphlets and the like, and clips mounted on the holder at the upper and lower ends thereof and having front and rear legs, the front legs being engageable with the books, magazines, catalogues, pamphlets and the like and the rear legs being located within the rear channel. 30

2. A bookbinder comprising a holder of a length to extend from the top to the bottom of books, magazines, catalogues, pamphlets and the like, 35 and consisting of a single piece of sheet metal bent at spaced points along longitudinal lines to provide front side flanges and a connecting web portion and thereby form a front channel to receive books, magazines, catalogues, pamphlets and the like, the metal at the said front flanges being bent rearwardly against the front flanges and extended rearwardly beyond said web to provide rear side flanges and form a rear channel, and means located at the ends of the holder and extending into the front and rear channels and detachably retaining the books, magazines, catalogues, pamphlets and the like in the front channel. 40

3. A binder for books, magazines, pamphlets, catalogues and the like, comprising a holder having a channel, a clip mounted on the holder at the channel and engageable with the books, magazines, catalogues, pamphlets and the like to secure the same to the holder, and an end closure 55 for the channel extending across the same for retaining the clip in its engaging position and having means detachably engaging the side walls of the channel.

4. A binder for books, magazines, pamphlets, catalogues and the like, comprising a holder having a channel, a clip mounted on the holder at the channel and engageable with the books, magazines, catalogues, pamphlets and the like to secure the same to the holder, and an end closure 65 mounted on the holder at an end thereof for retaining the clip thereon, said end closure being provided with means for detachably engaging the holder.

5. A binder for books, magazines, pamphlets, catalogues and the like, comprising a holder having a channel, a clip mounted on the holder at the channel and engageable with the books, magazines, catalogues, pamphlets and the like to secure the same to the holder, and an end closure 70 75

mounted on the holder at an end thereof for retaining the clip thereon, said holder being provided with arms extending into the said channel and having means for detachably engaging the 5 walls thereof.

6. A bookbinder comprising a holder having a channel and forming a support for books, magazines, catalogues, pamphlets and the like, and provided in the opposite walls of the channel 10 with slots, a book engaging clip mounted on the holder at an end thereof, and a closure member for retaining the clip in position on the holder, said closure member being provided with arms extending into the channel and having laterally 15 projecting lugs engageable with the slots of said walls.

7. A bookbinder comprising a holder having a channel and forming a support for books, magazines, catalogues, pamphlets and the like, and 20 provided in the opposite walls of the channel with slots, a book engaging clip mounted on the holder at an end thereof, and a closure member for retaining the clip in position on the holder, said closure member being provided with arms 25 extending into the channel and having laterally projecting lugs engageable with the slots of said walls and having shoulders for holding the end closure against outward movement.

8. A bookbinder comprising a holder having a 30 channel and forming a support for books, magazines, catalogues, pamphlets and the like, and provided in the opposite walls of the channel with slots, a book engaging clip mounted on the holder at an end thereof, and a closure member for retaining the clip in position on the holder, said closure member being provided with arms 35 extending into the channel and having laterally projecting lugs engageable with the slots and provided with beveled ends to facilitate the insertion of the closure member in the holder.

9. A bookbinder comprising a holder having a channel and forming a support for books, magazines, catalogues, pamphlets and the like, and provided in the opposite walls of the channel 45 with slots, a book engaging clip mounted on the holder at an end thereof, and a closure member for retaining the clip in position on the holder, said closure member being provided with arms extending into the channel and having laterally 50 projecting lugs provided at one end with a shoulder for holding the closure element against outward movement and beveled at the other end to facilitate the insertion of the closure member in the holder.

55. 10. A bookbinder comprising a holder having a channel and forming a support for books, magazines, catalogues, pamphlets and the like, and provided in the opposite walls of the channel with slots, a book engaging clip mounted on the 60 holder at an end thereof, and a closure member

for retaining the clip in position on the holder, said closure member being provided with arms extending into the channel and having laterally projecting lugs engageable with the slots and provided at each end with a shoulder for engaging an end wall of the slots. 5

11. A bookbinder comprising a holder having a channel and forming a support for books, magazines, catalogues, pamphlets and the like, and provided in the opposite walls of the channel 10 with slots, a book engaging clip mounted on the holder at an end thereof, and a closure member for retaining the clip in position on the holder, said closure member being provided with arms 15 extending into the channel and having laterally projecting lugs engageable with the slots and beveled at each end to facilitate the introduction of the closure member in the holder and enable the same to be readily removed therefrom without a key. 20

12. A bookbinder comprising a holder and spring clips for securing books, magazines, catalogues, pamphlets and the like to the holder, said clips each being composed of front and rear legs and a connecting portion, the front leg being of 25 greater length than the rear leg and having a relatively large terminal loop and the rear leg being provided with an angular bend engaging the holder at a point intermediate the ends of the front leg and arranged at an angle to the engaged portion of the holder and providing an intervening space to permit pivotal movement of the rear leg and an adjustment of the front leg without disturbing the position of the front leg in parallelism with the holder, whereby the front 35 leg is adapted to lie flat against books of different thicknesses.

13. A bookbinder comprising a holder forming a support for books, magazines, catalogues, pamphlets and the like, and a clip located at an end 40 of the holder and composed of front and rear legs and a resilient curved connecting portion, the rear leg being arranged at an acute angle to the front leg and bearing at its free end against and fulcrumed thereat on the holder and forming 45 an intervening space between it and the holder to permit pivotal movement of the rear leg toward the engaged portion of the holder and the front leg being straight and in substantial parallelism with the holder when in engagement with a book, said connecting portion forming with the front and rear legs a tapering loop and cooperating with the fulcrumed rear leg to permit the front leg to be spaced different distances from the holder without disturbing its parallelism with 50 relation to the holder, whereby the front leg is adapted to lie flat against a book regardless of the thickness of the same. 55
